CIGARETTE ROLLER

Norman W. Cummins, Louisville, Ky., assignor to
 R. J. Reynolds Tobacco Company, Winston-
 Salem, N. C., a corporation of New Jersey

Application January 23, 1941, Serial No. 375,600

4 Claims. (Cl. 131—51)

This invention relates to cigarette rollers of the type wherein the closing movement of a cover, hinged to the rear end of a case, is utilized to actuate a transversely-disposed roller in the case into engagement with an overlying longitudinally-extending apron for rolling tobacco on the apron into a cylindrically shaped charge.

The principal object of the invention is to provide a device of this character which is more compact and substantially less expensive to manufacture than heretofore, without sacrificing its effectiveness or otherwise subjecting it to any disadvantage.

A cigarette roller embodying the invention is illustrated in the accompanying drawing wherein:

Figure 1 is a plan view of the roller in the open position;

Figure 2 is a section taken along line 2—2 of Figure 1;

Figure 2a is an enlarged fragmentary view taken, along line 2—2 of Figure 1, to show the relation of the parts adjacent the hinge;

Figure 3 is a section taken along line 3—3 of Figure 1 but with the device in a partially closed position;

Figure 3a is an enlarged fragmentary view taken, along line 3—3 of Figure 1, to show the relation of the parts adjacent the front end of the apron.

The cigarette roller as illustrated in the drawing includes a case 1 and a cover 2, swingably connected together at their rear ends by means of a hinge pin 3. The cover 2 is conventionally secured at its rear corners to the hinge pin 3 by hinge elements 2a. The case 1 is secured to hinge pin 3 by passing the pin through openings in hinge elements 1a which form an integral part of the guide rails 8 and by securing the guide rails fixedly to the case 1 as will be hereinafter described. The case and cover are preferably made substantially identical in size and shape so that they may be advantageously fashioned of light gauge sheet metal at a minimum of expense. The case, however, is provided, adjacent its front end, with a transversely disposed cigarette discharging opening 4.

The closing and opening movements of the cover are utilized to move a conventional, transversely disposed roller 5 forwardly and rearwardly along the case in the customary manner; hence the ends of the roller 5 are connected, by means of a bail 6, to the inner surface of the cover intermediate its ends. The ends of the bail 6, adjacent the roller, pass through guide-ways 7 formed in guide-rails 8, which are mounted at opposite

sides of the case to extend between front and rear ends thereof, in order to guide the roller during its movement along the case. While the rails 8 may be fabricated and secured in any suitable manner, they may be inexpensively manufactured by upwardly turning the side margins of a suitably shaped single sheet of metal 9 and inexpensively secured in place by fastening the sheet 9 mechanically to the inner surface of the case 1 through the conventional use of lips 9a integrally formed on sheet 9 to project through appropriate slots in case 1 with the projecting ends peened over the case. This mode of securing is conventional, having been in wide use prior to this invention, and forms no part of this invention. The sheet 9 likewise is provided with a cigarette discharging opening corresponding in shape and location to the cigarette discharging opening 4 in the case 1.

In cigarette rollers of this type, the cover actuated roller 5 is forced, during its forward movement along the case, into tobacco rolling engagement with an overlying apron 10 extending longitudinally between the front and rear ends of the case. The front end of this apron is conventionally anchored to the case by securing it to an axle 11 carried by the case adjacent the rear edge of the cigarette discharging opening 4. The axle 11 is loosely clamped to the case and held in its apron anchoring position by extending the ends of the axle underneath the guide rails 8. The bottom wall of the case supports the axle while a slight slope in the bottom wall of the case prevents the axle from traveling rearwardly away from the opening 4. A corresponding but oppositely disposed slope in the lower edges of the guide rails 8 prevents the axle from moving forwardly over the opening 4.

Heretofore, the rear end of the apron 10 has been anchored to the case by suitable means mounted on the case adjacent its rear end. In accordance with the present invention the rear end of the apron is anchored directly to hinge pin 3. This method of anchoring the apron has several distinct and substantial advantages. For example, it enables the overall length of the device to be reduced as much as 10%, thereby correspondingly rendering it more compact and reducing its cost without, at the same time, subjecting it to any other disadvantage. More importantly, however, it not only eliminates the labor and materials involved in providing special means for anchoring the rear end of the apron but anchors the rear end of the apron to a part which is openly accessible and one to which the

apron may be easily and quickly secured without interfering with or otherwise complicating the normal assembly of such part. As a result of this method of anchoring the apron, the manufacturing cost of the cigarette roller as a whole can be and has been reduced by approximately 20%.

Since the operation of devices of this general character are well understood, it should suffice to say that when the device is fully opened, i. e. opened to a point where both the case and the cover lie flat, the apron is depressed around the front side of the roller 5 to form a loop which is then filled with tobacco, the device then closed about half way, a gummed cigarette paper 12 is then wetted and placed upon the apron with its gummed margin facing upwardly adjacent the rear edge of the discharge opening 4 and the device thereupon completely closed during which the cigarette is rolled, sealed and discharged through opening.

Having described my invention, I claim:

1. A cigarette roller comprising: a case; a cover; a hinge pin to which the rear ends of the case and cover are hinged; a cover-actuated roller transversely disposed in the case for movement forwardly and rearwardly along the case during the closing and opening movement of the cover; and a roller-actuated tobacco-rolling apron overlying the roller and extending longitudinally of the case with its front end anchored to the case and its rear end anchored to the hinge pin.

2. A cigarette roller comprising: a case; a cover; a hinge pin having each of its end portions hinged to both case and cover leaving the intermediate portion of the pin exposed and unobstructed; a cover-actuated roller transversely disposed in said case for movement forwardly and rearwardly along the case during the closing and opening movement of said cover; and a roller-actuated tobacco-rolling apron overlying said roller and extending longitudinally of said case with its front end anchored to said case and its rear end anchored to the exposed portion of said hinge pin.

3. A cigarette roller comprising: a case having a bottom wall, upwardly extending side and end walls, and a transverse cigarette discharge opening in its bottom wall adjacent its front end; a guide rail arranged adjacent each side of the case to extend longitudinally from the front to the rear of the case, each rail having a longitudinally extending guide slot and being fixedly secured to the case; a cover; a hinge pin positioned adja-

cent the rear edge of both case and cover; means for hinging both case and cover adjacent their rear corners to the end portions of the hinge pin, the central portion of said pin being exposed and unobstructed; a roller transversely disposed in said case between the guide rails; roller-actuating means pivotally mounted on said cover and slidably mounted in said guide slots for rotationally carrying said roller forwardly and rearwardly in a predetermined path along the case during the closing and opening movements of said cover; an apron rod anchored to the case adjacent the rear edge of said discharge opening; and a roller-actuated tobacco-rolling apron overlying said roller and extending longitudinally over said case with its front end anchored to said apron rod and its rear end anchored to the exposed portion of the hinge pin.

4. A cigarette roller comprising: a case having a bottom wall, upwardly extending side and end walls, and a transverse cigarette discharge opening in its bottom wall adjacent its front end; a guide rail arranged adjacent each side of the case to extend longitudinally from the front to the rear of the case, each rail having a longitudinally extending guide slot and being arranged with its lower longitudinal edge fixedly secured to the bottom of the case and with its upper longitudinal edge projecting above the case; a cover having a top wall, and downwardly extending side and end walls; a hinge pin extending along the rear edge of both case and cover with its end portions passing through the guide rails of the case and being hinged to the rear corners of the cover and with its central portion remaining exposed and unobstructed; a roller transversely disposed in said case between guide rails; roller-actuating means pivotally mounted on said cover and slidably mounted in said guide slots for rotationally carrying said roller forwardly and rearwardly in a predetermined path along the case during the closing and opening movements of said cover; an apron rod anchored within and to the case adjacent the rear edge of said discharge opening; and a roller-actuated tobacco-rolling apron overlying said roller and extending longitudinally over said case with its front end anchored to said apron rod and its rear end anchored to the exposed portion of said hinge pin, said apron being operative during the forward movement of said roller to roll a cigarette and discharge it through said discharge opening.

NORMAN W. CUMMINS.
